UNITED STATES PATENT OFFICE

170,178

ASH TRAY

Robert Wood, Red Bank, N. J.

Application July 16, 1952, Serial No. 20,624

Term of patent 7 years

(Cl. D85—2)

To all whom it may concern:

Be it known that I, Robert Wood, a citizen of the United States, residing at Red Bank, State of New Jersey, have invented a new, original, and ornamental Design for an Ash Tray, of which the following is a specification, reference being had to the accompanying drawing, forming a part hereof.

Fig. 1 is a perspective view of an ash tray showing my new design;

Fig. 2 is a plan view thereof, and

Fig. 3 is a cross-sectional view of the ash tray, taken on line 3—3 of Fig. 2.

I claim:

The ornamental design for an ash tray, as shown.

ROBERT WOOD.
